UNITED STATES PATENT OFFICE.

THOMAS A. MEEHAN, OF ASTORIA, NEW YORK, ASSIGNOR TO OLD MASTERS LITHO.
CORPORATION, OF NEW YORK, N. Y., A CORPORATION OF NEW YORK.

DISPLAY DEVICE.

Application filed April 22, 1926. Serial No. 103,807.

This invention relates to display devices, and has particular reference to those which are formed as a self supporting unitary structure.

5 Among the objects of this invention is to provide a display device which can be made of a piece of sheet material such as paper and provide a main or central picture or panel, and supporting means for the panel 10 which are adapted likewise for purposes of display or advertising.

Another object of this invention is to provide a display device which is formed with a minimum waste of material and preferably as a stamping or the like, the structure being of maximum simplicity, and being set up with the greatest ease.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a view of a blank.

30 Fig. 2 is a front view of the finished display device.

Fig. 3 is a sectional view on the line 3—3 of Fig. 2.

Referring now more specifically to the drawings, I show my invention as being formed of a single piece of cardboard or the like and assuming generally the form of a blank 10, which is substantially rectangular. A pair of score lines 11 and 12 which 35 are substantially parallel to each other extend transversely from certain points spaced from the top of the blank down to the bottom of the blank. Slits or cuts 13 and 14 extend from the upper ends of the score lines 40 to the top of the blank. A pair of score lines 15 and 16 extend inward from the junctions of the slits 13, 14 with the score lines 11, 12. The score lines 15 and 16 constitute hinge lines and are therefore in alignment with each other, their inner ends being spaced apart to provide an unbroken central panel P therebetween. Preferably 45 a pair of slits or cuts 17 and 18 extend downward from the inner ends of the hinge lines 50 in spaced relation to the vertical score lines

11, 12 and positioned inward thereof. Thus it will be seen that the blank is divided up so as to provide a central panel, and a pair of wing members to support the panel positioned at the sides thereof, said wing members being of angular construction in that they consist each of the main or outer panels 19 and 20 and of the auxiliary braces or flanges 21 and 22. The central panel P is somewhat longer than the wing members, 60 its upper edge 23 projecting above the wing members in the blank, while its lower edge 24 projects below said members. When the device is set up for display, however, the height of the various parts will appear to be 65 substantially the same, since the central panel P will assume a rearwardly inclined position by tilting about the hinge lines 15, 16 due to its projecting lower portion. The wings are adjusted forwardly about the 70 score lines 11, 12 thus rendering the device 75 self supporting in an efficient manner.

The panel P is intended to contain the main picture or story intended to be conveyed to the public, all parts thereof being 80 utilized. The panels 19 and 20 of the wing members are likewise intended to contain display or advertising matter. As thus set up, the display device assumes a particularly 85 attractive and neat appearance.

The specific arrangement of cuts and score lines in the blank can be readily varied to suit different conditions or advertisements. Thus the form of the slits 17, 18 is preferably 90 such as to follow the outline of the picture on the panel P where such picture is disposed adjacent to said slits. Toward the bottom of the device, the slits 17, 18 may assume an ornamental form as shown at 17^a 95 18^a. Slits 13, 14 may likewise be varied to enhance the attractiveness of the device, as by having the central panel cut inwardly at 25. Generally, however, the various cuts and score lines are so arranged as to provide approximately horizontal score or hinge 100 lines in alignment with each other extending from the central panel to the wing members, a plurality of cuts being formed at each of the hinge lines one of which extends upward and the other downward from its 105 respective hinge line to separate the central panel from the wing members, and permit said panel to be inclined with the vertical about the hinge lines as an axis. This invention wherein a pair of horizontal hinge 110

lines is utilized in connection with a central unbroken display panel permits of a highly simplified construction of a self supporting display device.

I claim:

1. A display device comprising a body having two score lines extending in substantially parallel relation approximately from the top to the bottom of the device providing a central portion and two wing portions, the central portion being slotted adjacent to said score lines and scored by aligned lines extending from the ends of said slits approximately at right angles to the adjacent first mentioned score lines thus providing a central panel in said central portion of the device which is adapted to be positioned at an incline with the vertical.
2. A display device comprising a body having two score lines extending in substantially parallel relation from points in spaced relation to the top of the device approximately to the bottom thereof, the device being cut from the upper ends of said score lines approximately to the top of the device, substantially horizontal score lines being provided extending in alinement from the points aforesaid inward and with their inner ends in spaced relation to each other, and cuts being provided extending from

said inner ends downward so as to permit the panel formed between the last mentioned cuts to be inclined about the horizontal score lines as a hinge.

3. A display device having a central panel, wing members to support the panel at the sides thereof, and hinge means between the central panel and the wing members formed by approximately horizontal score lines in alinement with each other extending from the central panel to the wing members, and a plurality of cuts at each score line one of which extends upward and the other downward to separate the panel from the wing members and permit the same to be inclined with the vertical about the horizontal score lines as the hinge axis.

4. A display device having a central panel, and wing members at the sides of the panel to support the same, said wing members being of angular cross section, said panel being hingedly connected to said wing members along a horizontal line at the sides of the panel whereby the panel can be inclined at an angle with the vertical while being supported.

In testimony whereof I affix my signature.

THOMAS A. MEEHAN.
